UNITED STATES PATENT OFFICE.

JOHN H. CLARK, OF WEST CONCORD, NEW HAMPSHIRE.

RAILROAD-TIE.

No. 831,535.

Specification of Letters Patent.

Patented Sept. 25, 1906.

Application filed November 22, 1905. Serial No. 288,587.

To all whom it may concern:

Be it known that I, JOHN H. CLARK, a citizen of the United States, residing at West Concord, in the county of Merrimack and 5 State of New Hampshire, have invented a new and useful Railroad-Tie, of which the following is a specification.

My invention relates to certain new and useful improvements in metallic railroad-ties, and has for its object to provide a tie that is very simple and cheap in construction and one that is very effective in use.

Another object of my invention is to provide a tie with fastening means, so that the 15 rail can be easily and quickly secured thereon.

A further object of my invention is to provide the tie with outwardly-projecting flanges, so that a greater bearing-surface will be obtained than in other ties of this character.

With these objects in view the invention consists of the novel features of construction, combination, and arrangement of parts hereinafter fully described, and pointed out in the 25 claims.

In the drawings forming a part of this specification, Figure 1 is a perspective view of my improved tie, showing the rail secured thereon. Fig. 2 is a top plan view of the tie. 30 Fig. 3 is a side elevation of the tie, one of the flanges being in section, showing the means of securing the rail thereon. Fig. 4 is a longitudinal central sectional view of the tie, showing the means of securing the rail. Fig. 5 is an end view of the tie. Fig. 6 is a perspective view of one of the rail-securing members detached.

Referring to the drawings, A indicates a hollow metal casing forming the body of the 40 tie, having open ends, a curved bottom A', and a flat top A², provided with a longitudinal slot A³, formed therein. Projecting out from the top on each side adjacent each end are flanges A⁴, supported by braces A⁵, secured to the sides of the casing.

Secured in each end of the top of the casing in alinement with the braces A⁵ is a brace-rod A⁶, connecting the top and bottom of the casing and adapted to relieve the side of the casing where the strain is the greatest. Spaced

openings A⁷ are formed in the top on each side of the brace-rod. The flanges A⁴ are provided with openings A⁸ adjacent their ends in alinement with the openings in the top of the casing. U-shaped bolts B are 55 adapted to extend up through these openings and through the opening C', formed in the clamping-block C. The block C is provided with a cut-away portion C², which is adapted to fit over the flange of the rail and to be securely clamped thereto by nuts B', which are adapted to be screwed down on the bolts B and brought into engagement with a wooden block D, secured in a square recess C³, formed in the block C around the opening C' and relieve the bolts of the strain and prevent them from breaking.

Having thus fully described my invention, what I claim as new, and desire to secure by Letters Patent, is—

70

1. In a device of the kind described, the combination with a hollow casing provided with flanged members projecting therefrom, of openings formed in the top of the casing, and flanges and means projecting up through 75 said openings for locking the rail to the tie, for the purpose described.

2. In a device of the kind described, the combination with a hollow casing provided with outwardly-projecting braced flanges, 80 spaced openings formed in the top of the casing and in the flanges, bolts projecting up through said openings, and recessed blocks carried by said bolts for the purpose described.

3. In a device of the kind described, the combination with an open-end casing provided with braced flange members, spaced openings formed in said flanges, spaced openings formed in the top of the casing, a brace 90 secured in the casing adjacent each end, U-shaped bolts extending up through the said apertured openings, blocks arranged on said bolts, recesses formed in said blocks, and a wooden block arranged in each recess, for the 95 purpose described.

4. In a device of the kind described, the combination with a hollow open-end casing provided with outwardly-projecting braced flanges adjacent each end, of braces secured 100

in the casing adjacent each end in alinement with the said braces, spaced openings formed in the casing and in the flanges, U-shaped bolts projecting up through said openings, 5 clamping-blocks arranged on said bolts, recesses formed in said blocks, blocks of wood arranged in said recesses, and nuts arranged

on said bolts adapted to engage said blocks, for the purpose described.

JOHN H. CLARK.
